UNITED STATES PATENT OFFICE

PIERRE L. A. MOREAU, OF PARIS, FRANCE, ASSIGNEE TO M. H. DETRICK COMPANY, OF CHICAGO, ILLINOIS, A CORPORATION OF ILLINOIS

FURNACE ARCH CONSTRUCTION

Application filed March 23, 1929. Serial No. 349,294.

This invention relates to the construction of arches for furnaces, particularly arches of the suspended type. It has to do principally with the construction of terminal portions of arches and portions in which the direction of the arch surface changes.

A general object of the invention is the provision of a construction which will possess the usual advantages of suspended arches and certain further and novel advantages in regard to ease of assembly and repair, and accommodation of variations in size of the component refractories.

More particularly, an object of the invention is the provision of a radial or convex furnace arch construction which may be assembled in conjunction with a flat suspended arch, in such relationship as to afford effective protection for the metallic supporting members of the structure, but without involving any particular relationship in the relative widths of the refractories used in the flat arch and in the radial arch.

Yet another object is the provision of a novel form of refractory whereby radial arches possessing advantages mentioned above may be constructed, and particularly qualified to give the radial arch a desirable flexibility and avoid the subjection of its constituent refractories to pressures, such as might tend to break them from their mountings, consequent upon thermal expansion or contraction of the structure.

Other and further objects of the invention will be pointed out or indicated hereinafter or will appear to one skilled in the art upon an understanding of the invention or its employment in practice.

In the accompanying drawings forming a part of this specification I show one construction representative of one form of embodiment of the invention. It is understood that this is presented merely by way of illustration and is not to be accorded any interpretation for the purpose of limiting the appended claims short of the true and most comprehensive scope of the invention in the art.

In the drawings

Fig. 1 is a longitudinal section of the nose or terminal end of a suspended furnace arch;

Fig. 2 is a detail, on a larger scale, illustrating in side elevation the form of a radial arch tile and its means of support;

Fig. 3 is an end elevational view of an arch construction with some of the radial tiles removed, and

Fig. 4 is a perspective illustration of a hanger for the radial tiles.

The employment of suspended arches for furnaces, wherein the arch refractories are suspended on metallic supporting members, has become quite general because of the recognized advantages of suspended arches, particularly where the span of the arch is large and the conditions of service severe. The wear on the arch refractories is likely to be particularly severe in portions of the arch where the surface exposed to the furnace heat and combustion gases changes direction, as at the terminus of the arch within the combustion chamber. The refractories in such portions of the arch are likely also to be subjected to the greatest heat and consequently to the greatest thermal expansion. The circumstances require that special consideration be given to the construction of these portions of the arch, with the object of safeguarding the refractories against the destructive influences to which they are exposed, affording the metallic supporting members adequate protection from the furnace heat, and enabling the refractories to be replaced with facility.

The present invention provides a construction wherein tiles of relatively small size may be employed in a radial or salient arch portion, the tiles being suspended individually so as to have a desirable freedom of movement and thus relieve their supporting parts of breaking strains, and whereby a tight or closely jointed refractory arch may be formed without the necessity of holding the tile to closely accurate dimensions.

The nature of the invention will be most quickly understood by reference to the example shown in the drawings. In the construction here illustrated, let it be understood that the reference numeral 10 designates supporting beams which extend over the furnace chamber, being suitably supported on the furnace walls or other appropriate support

so as to maintain them at the desired elevation. From these beams cast iron arch bars 11 are suspended by means of hangers 12. These arch bars are provided with marginal flanges 11^a which constitute retaining supports for the arch tiles 14. The latter, as seen in Fig. 3, are of generally rectangular form and are provided with T-shaped slots adapted to accommodate the flanges 11^a on the lower portion of the web of the arch bar 11, so that the refractories 14 may be suspended on the flanges 11^a, face to face, as shown in Fig. 1. A plurality of the courses of refractories 14, thus suspended on arch bars 11, are arranged side by side, as in Fig. 3, to form a flat suspended refractory arch. Where it is desired to change the direction of the arch surface vertically, as at the terminus of the arch, supporting bars or brackets, as illustrated by the bracket 15, are arranged, being suitably supported in position and provided with hanger supports 15^a. In the construction illustrated the brackets 15 are supported directly on the ends of the arch bars 11, but it is obvious that they may be supported in any other suitable fashion. Upon the hanger supports 15^a are supported the tile hangers 16, same preferably being susceptible of adjustment to different elevations. The hangers here illustrated, as shown in detail in Fig. 4, are cast iron members formed with oppositely disposed jaw portions 16^a affording an intervening slot with overhanging suspension lugs 16^b adapted to engage over the hanger supports 15^a, and having ledge portions 16^c projecting forwardly from the webs of the jaw portions. The jaw portions preferably are deflected, as best seen in Fig. 2, so that the supporting lugs 16^b overhang the ledges 16^c. The ledges 16^c preferably are straight longitudinally, but curved transversely so as to have a channel-like form. They may be readily slid onto and off of the hanger supports 15^a, and when supported thereon are susceptible of swinging movement. A suitable stop, here afforded by the end of the arch bar 11, is arranged to limit the movement of the lowermost hanger in one direction. A row of these hangers is arranged along the margin of the flat arch, as illustrated in Fig. 3, so that the ledges 16^c of the several hangers are approximately in alignment. The length of the ledges 16^c preferably is such that there are only narrow intervening gaps between the ends of juxtaposed hangers. Upon these ledges are suspended the radial tile 17. These are wedge-shaped, their front and rear faces being in converging relationship, and their lateral faces being parallel. At their narrow ends they are formed with lateral grooves or notches 17^a, to form overhanging suspension lugs having the hanger-engaging part 17^b approximately on the median line $m-n$ of the tile, and the slightly depending nose part 17^c

in-set from the rear face of the tile. The hanger-engaging parts 17^b rest on the up-turned margins of the ledges 16^c, leaving a clearance between the nose portions 17^c and the channel surface of the ledges. Thus the tiles 17 may rock on the margins of the ledges, the tiles thus being afforded a substantial extent of arcuate movement with respect to the hangers. The length of the hanger-engaging part 17^b is preferably appreciably greater than the width of the up-turned margins of the ledges 16^c upon which they rest, so that the tile is afforded a range of shifting movement in front-to-rear directions, this for accommodation of expansion in the arch structure, so that injurious stresses will not be imposed on the outer ends of the tile lugs. One tier of the refractories 17 having thus been positioned on the lowermost row of hangers, a second row of hangers is placed on the brackets 15, and a second tier of refractories 17 arranged thereon as above described. The third row of hangers and third tier of refractories 17 are similarly positioned.

By virtue of this construction, the width of the refractories 17 may be made very much less than the width of the refractories 14. As shown in Fig. 3, the refractories 17 are approximately one-third of the width of the refractories 14. The length of the refractories 17 should be such that their lower end faces will merge with the lower end faces of the associated refractories 14 and with associated refractories 17, so as to give the arch a regular or uniform lower surface. Substantial advantage is gained by having the refractories 17 of relatively small size. In the first place, this facilitates the manufacture and decreases their cost, permits their density to be more readily controlled and enables them to be more readily and thoroughly burned in the course of manufacture. These factors contribute to their uniformity of quality and also to their ability to resist the destructive wearing influences of the furnace heat and erosion when in use. In the second place, the small size of these refractories minimizes the area of the individual refractories exposed within the furnace, thus reducing the opportunity for destructive overheating of the refractories. In the third place, the use of small component tiles in the arch gives the arch structure as a whole a desirable flexibility, permitting it to accommodate thermal expansion and contraction of the refractories without subjecting their supporting portions to breaking strains. As a result of these various factors, the radial arch is particularly qualified to avoid spalling and rapid erosion of the component refractories. Moreover, the construction greatly facilitates not only the original assembly of the structure, but also the replacement of the radial refractories when it becomes necessary to renew them.

Another distinct advantage of the construction resides in the fact that the width of the radial refractories does not have to be held definitely to a certain proportion of the width of the associated refractories 14. This is brought out in Fig. 3, wherein it will be observed that while the aggregate width of the first group of radial refractories, designated A, is the same as that of the aligned course of the refractories 14, the aggregate width of the second group of radial refractories somewhat exceeds the width of the associated course of the refractories 14, the terminal refractories of the second group overlapping the third course of the refractories 14. Thus variations in the width of the refractories 17, do not in any manner affect the tightness of the arch, as the juxtaposed refractories may always be placed in close abutment across the entire width of the arch, any discrepancy in the aggregate width being accommodated in the overlap of the margin of the arch over the furnace wall. The refractories 17 are of a shape which may be manufactured with facility and without disproportionate loss from spoils in drying and burning. It will be observed that the support engaging portion 17^b is quite close to the part which connects the overhanging lug to the body portion and approximately over the center of gravity of the tile, and because of this feature the overhanging lug is not subjected to any great leverage from the weight of the tile, such as would be the case if the tile were supported on the extending part of the lug, such as the nose 17^c. This nose portion, it will be observed, does not carry any of the weight of the tile, but functions simply as a retaining member to aid in keeping the tile from slipping off from the hanger. It will be apparent also that the radial tiles, as supported in the arch structure, are susceptible of movement in the arc of the arch and also transversely of the arch, without decreasing the security of their support or imposing excessive stresses on their supporting portions.

What I claim is:

1. In furnace arch construction, in combination, a plurality of hangers disposed in a row and having tile engaging portions disposed in alignment end to end to form a ledge having an up-turned outer margin, side slotted refractories supported on said hangers and bearing thereon solely on said up-turned margin and movable longitudinally thereof from one to another of said hangers, said refractories depending below said ledge and arranged in abutment to form an arch portion.

2. In furnace arch construction, in combination, a hanger formed with a channel-like ledge, and a wedge-shaped tile formed with a lateral groove adjacent its narrower end, said groove being of sufficient width to per-

mit introduction of said ledge, and the part of the tile constituting the top of said groove having adjacent its inner end a support engaging portion adapted to rest on the margin of said ledge and maintain the balance of 70 said part out of contact with the ledge when the tile is suspended thereon.

3. As an article of manufacture, a furnace arch portion consisting of a refractory tile having converging marginal sides and parallel lateral faces, said tile being provided adjacent its narrower end with a transverse groove extending inwardly from one of the converging faces and opening at the lateral faces, the portion of the tile overhanging 80 said groove being formed adjacent its inner end with a support engaging portion approximately on the longitudinal median line of the tile, and at its outer end with a depending nose portion.

4. As an article of manufacture, a furnace arch portion consisting of a wedge-shaped refractory tile provided adjacent one end of one of its converging sides with a transverse lateral groove, a portion of the tile overhanging said groove being formed adjacent its inner end with a flat support engaging portion and adjacent its outer end with a depending nose portion, the support engaging portion extending from approximately the median line of the tile for an appreciable distance so as to permit the tile to shift on a supporting member engaging the same between said depending nose and the inner limit of said slot.

In testimony whereof I have hereunto subscribed my name.
